UNITED STATES PATENT OFFICE.

RAYMOND M. ANDERSON, OF DETROIT, MICHIGAN, ASSIGNOR TO GEORGE M. HOLLEY,
OF DETROIT, MICHIGAN.

CARBURETOR.

Application filed August 14, 1920. Serial No. 403,585.

To all whom it may concern:

Be it known that I, RAYMOND M. ANDERSON, citizen of the United States, residing at Detroit, in the county of Wayne and State 5 of Michigan, have invented certain new and useful Improvements in Carburetors, of which the following is a specification.

The invention relates to improvements in carburetors having means for supplying fuel 10 to a high speed nozzle and a low speed fuel receiver having a restricted opening through which a jet of fuel issues when the throttle is substantially closed, said low speed receiver being constructed to allow fuel to 15 stand therein above the level of the fuel in the high speed nozzle so as to provide a supply of fuel available to cause an increased flow from the high speed nozzle upon a sudden opening of the throttle valve thereby 20 causing the engine to run quite regularly and to prevent "stalling" thereof. It is therefore, a primary purpose of this invention to provide a carburetor having a reserve supply of fuel which accumulates in the low 25 speed fuel receiver and which stands above the level in the high speed nozzle, so that during that period in which the throttle is being rapidly opened, the surplus fuel from said receiver is supplied to the high speed 30 nozzle to assist in maintaining a constant mixture and to permit a rapid acceleration of the engine.

In the accompanying drawings, I have shown a preferred embodiment of my invention, but it will be clearly appreciated that such a disclosure is merely made for the purpose of illustrating one convenient form of the invention and that various changes can be made without departing from the 40 spirit of the appended claims.

In the drawings, Fig. 1 shows a vertical section of a carburetor in a somewhat diagrammatic form.

Fig. 2 illustrates a detail showing of one 45 of the parts of the carburetor.

Fig. 3 is a fragmentary sectional view showing the low speed fuel receiver in operation.

Fig. 4 is a section on line 4—4 of Fig. 5 of 50 a commercial type of carburetor embodying this invention.

Fig. 5 is a similar section of line 5—5 of Fig. 4.

Referring now more particularly to the 55 drawings wherein like reference character

indicate corresponding parts, the carburetor comprises the usual casing having an air inlet 1 therein at the atmospheric side of the throttle valve. Controlling said air inlet, there is a choke valve 2 which may be of 60 the conventional type and is usually operated upon the starting of the engine. The interior of the carburetor is formed with a venturi 3, which is common in carburetors of this general type and into which venturi the fuel from the constant level reservoir 4 is discharged by means of a high speed jet which will be later described.

At one side of the carburetor, I provide the usual constant level supply chamber, 70 preferably having a float valve 4 therein, and I also provide in this chamber a needle valve 5 for regulating the passage of fuel through a restricted opening 6 in the constant fuel supply chamber which fuel passes from said chamber into the fuel passage 7, communicating with the auxiliary fuel supply chamber 8, the low speed fuel receiver and high speed jet which will be hereinafter described.

The auxiliary supply chamber 8 is formed with a vented closure 9 whereby air may enter the top of this chamber. In this chamber there is also mounted a tube 11 suspended from the closure 9 and having therein a series of perforations 12 and a restricted bottom opening 13 from which fuel discharges. This chamber and tube retains a slight reserve supply of fuel and when the engine throttle is suddenly opened after the 90 engine has been idling the supply of fuel in this chamber 8 discharges through the enlarged opening leading to the fuel passage 7 and from said passage on to the high speed jet 17. It will be appreciated that when the engine is idling as shown in Figure 3, the fuel in the receiver 20 is rising upwardly in a stream and should the throttle valve 16 be suddenly opened it takes a slight period of time to reverse the direction of 95 flow of this fuel body so that it discharges through the jet 17. It is during this period the moment the throttle valve is open that the fuel in the auxiliary chamber 8 is supplied to the nozzle 17, thereby producing an immediate acceleration of the engine. When the engine again runs at slow speed sufficient fuel is fed from the float chamber and the chamber 8 again becomes refilled with fuel.

100 105 110

The passage 7, leading from the restricted opening regulated by the valve 5, communicates with a low speed fuel receiver 14 having a restricted opening 14^a at its upper end and also with the high speed nozzle 17 having an interior air passage communicating with the atomizing air conduit 18 leading from the main air inlet 1. The carburetor is, of course, controlled by the usual throttle 16 on the other side of which there is the mixture outlet 19. Entering the carburetor, adjacent the throttle valve when it is closed or partially closed, is the low speed outlet port 15 leading from the mixing chamber 15^a disposed in the wall of the carburetor.

From the foregoing description of the various parts, it will be clearly appreciated that when the engine is idling the throttle valve is in the position shown in Figs. 1 and 20 3 the combustible mixture is entering the mixing chamber as disclosed by the reference character A in Fig. 3 above the throttle valve. This is caused by air passing up through the channel 1^a from the main air inlet 1 around the restricted opening of the fuel receiver 14 where it commingles with the issuing jet of fuel, vaporizing the discharged fuel in the chamber 15^a, the vaporized mixture then passing on through 25 the port 15. The fuel in the low speed fuel receiver at this time stands substantially above the fuel level in the nozzle 17 and also above the level of the fuel in the constant fuel reservoir. Therefore, should the 30 throttle be suddenly opened as frequently occurs, in the operation of an engine, the suction would be entirely destroyed at the restricted opening of the low speed fuel receiver and an intense suction would be created at the high speed nozzle. The fuel standing in the low speed fuel receiver above the level of the fuel in the nozzle would then flow out through the high speed nozzle under its static head, and the discharge of 45 fuel from this high speed nozzle 17 would be thereby momentarily increased so as to supply the proper quantity of fuel upon the rapid opening of the throttle to permit a satisfactory acceleration and prevent a 50 "stalling" of the engine. This body of fuel in the low speed receiver maintained above the level of the fuel in the high speed nozzle therefore most satisfactorily acts to supply that needed additional quantity of fuel that 55 should issue into the mixing chamber the moment the throttle is opened. The regulated or restricted opening controlled by the valve 9 of course prevents this fuel from going back into the constant fuel reservoir and it must discharge through the high 60 speed nozzle.

It will be furthermore understood that when running idle or under a light load the throttle 16 is opened but slightly and some

fuel is broken up by the eddy formed thereby at the edge of the throttle opposite the fuel outlet 14. The fuel issuing from the restricted opening 14^a is also aspirated with air by-passed around the throttle 16 through the angular air passage 1^a.

Having thus described my invention, what I claim is:

1. A carburetor comprising a body having a constant level fuel reservoir and a mixing chamber adjacent said reservoir, a mixture outlet and a throttle valve in said mixture outlet, a fuel feeding nozzle extending into said mixing chamber, said carburetor being formed with a fuel receiver having its upper end extending to a plane above the fuel level maintained in said nozzle to permit fuel to stand in said receiver so as to be available to cause an increase of flow from the nozzle on opening movement of the throttle, a regulated connection from said constant fuel liquid reservoir to both said nozzle and said fuel receiver, said fuel receiver having a restricted outlet at its upper end for the discharge of a jet of fuel, said carburetor being formed with an opening for the passage of air past said restricted outlet and providing a mixing chamber for the air and fuel adjacent said outlet, the carburetor body being further formed with a passage extending from said last mentioned mixing chamber to a point adjacent said throttle valve, and an air vented auxiliary fuel reservoir in communication with said nozzle to supply an initial fuel charge to the nozzle upon an increased air flow past said nozzle.

2. In a carburetor, the combination with a constant level fuel reservoir and a mixing chamber, a throttle valve on the engine side of said mixing chamber, of a high speed fuel feeding nozzle discharging into said mixing chamber on the atmospheric side of said throttle, a fuel receiver in communication with said nozzle and extending to a plane above the level of the fuel in the nozzle to permit fuel to stand in said receiver so as to be available to cause an increase of flow from the nozzle on opening movement of the throttle a regulated source of supply from said reservoir to said nozzle and said fuel receiver, said fuel receiver having a restricted opening at its upper end for discharging a jet of fuel, an auxiliary air passage into which said jet discharges communicating with the mixture outlet passage on the engine side of the throttle valve and an air vented auxiliary fuel reservoir in communication with said nozzle to supply an initial fuel charge to the nozzle upon an increased air flow past said nozzle.

In testimony whereof he affixes his signature.

RAYMOND M. ANDERSON.
